UNITED STATES PATENT OFFICE.

FRANK E. HOUSH, OF WINTHROP, MASSACHUSETTS.

BOOK-COVER.

1,162,484.

Specification of Letters Patent. Patented Nov. 30, 1915.

Application filed April 14, 1915. Serial No. 21,433.

To all whom it may concern:

Be it known that I, FRANK E. HOUSH, a citizen of the United States, residing at Winthrop, in the county of Suffolk and 5 State of Massachusetts, have invented new and useful Improvements in Book-Covers, of which the following is a specification.

My invention is an improved cover for account books, designed to grasp the bound 10 edge or back of the book in such fashion that the cover may easily be applied or disengaged from the book proper and also so that the sides of the cover may be supported in a desired position, so that the 15 leaves, when the book is in use, will be flat, or approximately so.

In the drawings: Figure 1 shows a plan view of the preferred form of my cover; Fig. 2 is a cross-sectional view of the cover 20 shown in Fig. 1; Fig. 3 is an end view showing the cover and book combined, the engaging parts of the cover and book being in section; Fig. 4 is a section on line 4—4 of Fig. 1.

As is well-known account books, which often continue in use for years, compel a construction of a strength and permanence proportional to the hard and long continuous service they may be called upon to 25 stand. For this reason the paper and sewing of the book proper is of the stoutest, while the cover itself is heavy and solid and solidly secured to the bound edge of the leaves. The result is a massive and bulky 30 book, occupying in the safe in which it is kept, when not in use, a considerable space and heavy to handle when in use.

My new cover is especially useful in connection with books bound in accordance 40 with United States Letters Patent No. 1,083,539, dated January 6, 1914, and is designed to receive a book carrying a light flexible cover, as shown therein; and to give such a book the necessary support when in 45 use on the desk.

My cover is formed in three parts, namely, the center piece, A, formed of a strip of thin sheet metal or other suitable material, bent into a rectangular shape of 50 suitable size to receive the bound edge or back of the book proper, which, when it is inserted, makes a tight fit. One side of the frame A is closed by a covering piece, a, of wood or other suitable material, secured 55 to the frame or center piece A. To the

edges of the sides of the center piece are hinged two sides B and C which are preferably also of thin sheet metal. These sides are of a length and breadth suitable to cover the sides of the book which the cover is designed to receive and the edges of the metal on the sides corresponding to the top and bottom of the book are preferably turned over to form a narrow flange, b, for a purpose to be hereinafter indicated. On the 60 edge of these sides which corresponds with the front of the book one or more projecting lips, e, may be formed, perforated as shown, with which a suitable lock, such, for example, as is shown in United States Letters Patent No. 1,127,004, dated February 2, 1915, may be engaged. To the outside of the sides B and C is secured a light box D of wood, fiber-board, card-board or the like, preferably open on the side to which 65 the covers B and C are applied and preferably stiffened and supported by cross-members, d', one edge of which rests upon the bottom d² of the box D and the other edges of which are flush with the upper 70 edges of the sides and ends, d, of the box D, forming in combination with the sides B and C a multiplicity of closed cells.

The box D may be secured to the flanges, b, or otherwise secured to the sides B and 75 C. When so secured a cloth or leather covering is applied to cover the outer surfaces of the sides and center piece, for purposes of finish.

Such a cover as I have described is strong, 80 stiff and of insulating character. If desired it may be detached from the book proper when the book is to be stored in the safe or it may be allowed to remain and will then provide a cover having a dead air space 85 of heat insulating character. When in use on the desk it forms a cradle for the book proper permitting its bound edge or back, to drop below the level of the leaves, so that the latter lie flat or approximately so. One 90 cover may be used upon the desk to carry in turn several different books and the expense of duplicating covers may thus be avoided.

I claim:—

1. The cover above described, made up, 105 in combination, of a frame or center piece to receive the bound edge of the book and hollow sides hinged to the edges of the frame or center piece, said sides being made 110

substantially as thick as the center piece so as to rest flatwise on a table or the like when the cover is open.

2. The cover above described, made up, in combination, of a frame or center piece to receive the bound edge of the book, sheet metallic sides hinged to the edges of said center piece and a hollow member divided into a multiplicity of cells by interior parti-

tions applied to the outer side of the metallic sides to support and protect the same.

Signed by me at Boston, Massachusetts, this 31st day of March, 1915.

FRANK E. HOUSH.
